Assistant Examiner — Dustin Andrew Griffith

(57) **CLAIM**

The ornamental design for a holster hook, as shown and described.

DESCRIPTION

FIG. 1 is a top-front perspective view of a holster hook showing my new design;

FIG. 2 is a bottom-rear perspective view thereof;

FIG. 3 is a left elevational view thereof;

FIG. 4 is a right elevational view thereof;

FIG. 5 is a top plan view thereof;

FIG. 6 is a bottom plan view thereof;

FIG. 7 is a front elevational view thereof; and,

FIG. 8 is a rear elevational view thereof.

The broken lines depict portions of the holster hook that forms no part of the claimed design.
